OIL CONVERSION

Albert G. Peterkin, Jr., Bryn Mawr, Pa., assignor
to The Atlantic Refining Company, Philadelphia, Pa., a corporation of Pennsylvania

Application May 14, 1929. Serial No. 363,023

1 Claim. (Cl. 196—48)

My invention relates to conversion or cracking of hydrocarbon oils, particularly petroleum or components thereof of high boiling point, to produce lower boiling oils, such as gasoline, which 5 are suitable for use as motor fuels in internal combustion engines; more particularly my invention relates to the cracking of oils of high specific gravity, such as residual oil resulting from cracking or non-cracking distillation.

10 In accordance with my invention, oils of such high boiling point, high specific gravity and objectionable solid content or other properties which render them difficult and relatively costly to treat by usual cracking processes, are converted or cracked with relative ease and at comparatively low cost to form solid coke, suitable for use as fuel, lower boiling oil suitable for use as motor fuel or for further cracking to produce motor fuel, and gas which may be used 20 as fuel or in the manufacture of salable products, as, for example, higher alcohols or the like.

A distinct advantage of my invention is a highly efficient heat interchange between the charging stock introduced into the system and 25 the vapors evolved therein, thus necessitating the application of a minimum amount of heat from an external source to raise the charging stock to the desired temperature.

My invention relates to improvements in 30 cracking processes whereby hydrocarbon oils, particularly heavy oils, as for example, of a gravity of from about 10° to about 20° A. P. I., which may be obtained from distillation or crude petroleum, or which may be residual oil from 35 a cracking operation, or a heavy crude petroleum, can be economically cracked without dilution and without substantial carbon deposition on the still walls, thereby eliminating the necessity of frequent cleaning, and reducing deterioration of the still.

More particularly in accordance with my invention, a heavy oil, or a mixture of two or more heavy oils, of the type aforesaid, which has previously been heated to a suitable temperature below that of incipient cracking, is introduced into a chamber, preferably not externally heated, and simultaneously there is introduced into the chamber to raise the heavy oil to cracking temperature, a highly heated oil, 45 preferably reaction products from a cracking operation. Thus heat is applied to the heavy oil in the chamber by means of the highly heated oil, and substantial cracking of the heavy oil is effected, with the formation of volatile products, 50 which may be conducted from the chamber as fluid, and coke, which deposits in the chamber, this without need to subject the heavy oil to an externally heated surface.

Further in accordance with my invention, the 55 volatile products resulting from the cracking of

the heavy oil in the manner above described are conducted to suitable dephlegmating or fractionating apparatus wherein a liquid fraction whose properties are unsuitable to adapt it for use as motor fuel is separated. This fraction 65 is passed from the dephlegmator or fractionator into cracking apparatus and the products resulting from the treatment effected in such apparatus are introduced into the chamber aforesaid. By so operating, substantial cracking of 70 the fraction occurs whereupon there are produced hydrocarbons of still lower boiling point, and the products as a whole in their highly heated condition are used to crack the heavy oil.

Generically, the method and apparatus of my 75 present invention are those of my prior application Serial No. 320,778, filed November 21, 1928. My present invention is differentiated from my invention of my aforesaid application however, particularly in that the heavy oil, before introduction into the cracking or coking chamber, is 80 preheated to a lower temperature, to wit, to a temperature below that of incipient cracking. My present invention departs further from that of my aforesaid prior application in various respects, hereinafter appearing, such as preheating 85 of the heavy oil in one or more heat exchangers prior to introduction into the cracking or coking chamber, either directly from the preheating system aforesaid, or through a heating furnace, 90 which latter however, as to some aspects of my invention, may be omitted.

Referring to the drawing, 1 is a pipe equipped 95 with pump 2 which leads to the inlet end of coil 3 arranged in the upper portion of the fractionating column C. From the outlet end of coil 3 the line 4 leads to the coil or tubes 5 of heat exchanger H, from which line 7 controlled by valve 7a leads to the tubes 9 of furnace A, fired by burner a to which is supplied fuel, as gas. With the line 7 connects line 8 controlled by valve 8a leading to the lower portion of the chamber B. With line 100 8 connects the line 1a equipped with pump 2a and control valve 1b through which fresh charging stock, as for example, gas oil, may be fed into said line, thence into chamber B.

With the outlet of tubes 9 is connected line 10 105 which leads into the lower part of chamber B, preferably heat insulated by means of insulating material i; however, it shall be understood that this insulation is for heat economy and is not indispensable.

There connects with the upper part of chamber B a line 11 controlled by valve 11a which communicates with the lower part of heat exchanger H with the upper part of which there connects line 12 through which vapors from chamber B are passed from exchanger H to the lower portion 110 of the fractionating column C. Trapped line 13 controlled by valve 13a connects the lower part 115 120

of heat exchanger H with the lower part of fractionating column C. Line 14 controlled by valve 14a connects line 13 with pipe 15, which connects the lower part of the fractionating column C through pump 16 with the inlet end of tubes 17 of the furnace D, fired with gas or other suitable fuel delivered to the burner d.

From the outlet of the tubes 17 line 18 controlled by valve 18a extends into and downwardly 10 in chamber B, discharging into its lower portion.

The fractionating column C may be of any suitable type; the one illustrated having fractionating plates b equipped with downflow pipes e and vapor uptakes f with bubbler caps g. Line 15 19 connects the upper portion of the column with partial condenser E, in turn connected by line 19a to reflux proportioning device R having leading therefrom trapped line 19d controlled by valve 19e leading to the upper portion of the column C, 20 and line 19b controlled by valve 19c leading to the inlet of coil 20 in condenser K. From the outlet of the coil 20 line 21 leads to gas separator F, having lines 22 and 23, controlled by valves 22a and 23a, respectively, which serve respectively 25 to conduct gas and liquid from the system.

Adjacent the bottom of the chamber B may be provided a pipe 24, controlled by valve 25, for drawing off condensate or liquid oil during the starting period.

30 In carrying out my process in apparatus of the type described, heavy oil, as, for example, bottoms from the non-cracking distillation of Mid-Continent crude petroleum, having a gravity of 12° A. P. I., is fed by means of pump 2 through pipe 1 through the coil 3, line 4 and coil 5. In passing through the coil 3 the temperature of the oil is raised by vapors passing upwardly through the fractionating column C, as hereinafter described; and in passing through coil 5, in which 35 it is brought into heat interchange relation with vapors passing upwardly through the heat exchanger H, as hereinafter described, the temperature of the oil is further raised.

After passing through coil 5 the heated oil is 40 conducted through line 7 into tubes 9 of the furnace A where it is raised to the desired temperature. However, if desired, by regulating valves 7a and 8a, in lines 7 and 8, respectively, a portion of the oil leaving coil 5 may be passed directly 45 into chamber B, or all of the oil from coil 5 may be passed directly into said chamber through line 8.

Unheated oil, of any suitable character, generally fresh feed oil, may be introduced directly 50 into the chamber B through lines 1a and 8, either alone or in mixture with preheated oil, depending upon the setting of valve 8a. In either case the valve 7a may be open or closed, permitting or preventing oil to pass at the same time through 55 the heater tubes 9 into chamber B.

The temperature to which the oil is raised before it is introduced into the coking chamber B will depend upon the temperature of the highly heated products introduced into chamber B from 60 tubes 17, upon the relative proportions of those highly heated products to heavy oil, and upon the nature of the particular heavy oil introduced into the system through pipe 1 and/or pipe 1a. Such temperature is so regulated as to effect substantial 65 cracking of the heavy oil while in the chamber B, in which obtains any suitable pressure, as, for example 30 pounds per square inch gauge, thereby to form lower boiling hydrocarbon oils, 70 gas and solid coke. It is possible that it may be necessary 75 to raise the heavy oil to such temper-

ature that substantial cracking thereof will occur before it is introduced into the chamber B. Under such conditions the velocity of the heavy oil through the tubes 9 of the furnace A is so controlled that carbon deposition in the tubes 9 does not occur.

Vapors of products introduced into and/or formed in the chamber B are passed along with the uncondensed gases formed through line 11 into heat exchanger H where they are brought into heat exchange relation with the residual oil passing through coil 5. From the upper portion of the heat exchanger H the vapors are conducted through the line 12 into the lower portion of the fractionating column C. The vapors and gases pass upwardly through the fractionating column countercurrent to and in contact with reflux liquid which passes downwardly from plate to plate therein; the vapors are fractionated and separated into fractions of various boiling ranges.

The vapors which reach the portion of the fractionating column in which the coil 3 is located are partially condensed by heat exchange which takes place between them and the oil passing through that coil, and the condensate passes downwardly through the column to serve as reflux liquid. The vapors and gases uncondensed by contact with the coil 3 leave the column C through line 19 and pass into the partial condenser E where a portion of the vapors is con-

35 densed, and the condensate is passed through line 19a into reflux proportioning device R which may be adjusted to return to the column any desired proportion of the condensate as reflux, so that in case insufficient reflux is supplied by con-

40 densation of the vapors effected by coil 3, sufficient additional reflux may be supplied from the device R. That portion of the condensate which is not returned to the column C and the remaining uncondensed vapors pass through line 19b into the condenser K where the remaining vapors are liquefied. The condensate and uncondensed gases then pass through line 21 into gas

45 separator F where separation of the uncondensed gases from the liquid is effected. The uncondensed gases pass from the separator through line 22 to suitable gas storage (not shown), while the liquid is withdrawn through line 23 and 50 passed to suitable liquid storage (not shown).

55 That portion of the vapors which condenses in heat exchanger H is conducted through trapped line 13 into the lower part of the fractionating column C, or by regulating valves 13a and 14a in lines 13 and 14, respectively, all or a portion of such liquid may be passed through line 14 directly into line 15 which leads from the lower 60 part of the fractionating column. There is conducted through line 15 the liquid which collects in the lower part of the fractionating column, and by means of the pump 16 this liquid and the liquid passed into the line 15 through line 14, 65 constituting an oil of intermediate boiling point, such as gas oil, are pumped into the tubes 17 of the furnace D where the oil is maintained under such temperature and pressure as will cause 70 cracking of the oil passed through tubes 17. For example, in the tubes 17 the oil attains a temperature from about 750° F. to upwards of 1000° F., and the pressure upon the oil in tubes 17 is 75 determined by pump 16 and setting of valve 18a, 80 and may vary from atmospheric pressure to upwards of 1000 pounds per square inch gauge.

85 The highly heated products from the tubes 17 are conducted through line 18 into the lower portion of the chamber B, their pressure being suit- 90

ably reduced as they pass through valve 18a. In chamber B the highly heated products are brought into contact and heat exchange relation with the preheated heavy oil which has been introduced into that chamber through line 10 and/or line 8. This causes substantial cracking of the heavy oil in the chamber B, to form a lower boiling oil and gas, which pass in the fluid state from the chamber through line 11, and coke which deposits in the chamber and is from time to time removed therefrom.

There is passed from chamber B through line 11 into heat exchanger H a mixture of the volatile portion of the cracked products, introduced from tubes 17 into the chamber B, which portion comprises low boiling oils suitable for use as motor fuel and oils unsuitable for such use but which are suitable for recracking, with the volatile products, resulting from the cracking of the heavy oil in chamber B, which latter oil may comprise to a relatively large extent vapors of an oil suitable for cracking at high temperatures. In heat exchanger H the heavier portion of the oil is condensed due to loss of heat to the cooling medium, which may be charging stock as described, passing through the coil 5. The uncondensed portion of the vapors passes from the upper part of exchanger H through the line 12 into the lower part of the fractionating column C and upwardly therethrough countercurrent to and in contact with descending reflux liquid, as heretofore stated.

The drawing is a diagrammatic illustration of one form of my apparatus and is for the purpose of explaining my invention. Details, such as openings to permit removal of coke, and other structural modifications or features which are well known to those skilled in the art, are not shown. As an example of a modification, in lieu of the separate heat exchanger H, the coil 5 may be disposed in the lower part of the fractionating column C.

Moreover, while only one coking chamber B is shown, it shall be understood that a second coking chamber may be installed, and used during the removal of coke from the first.

It shall be further understood that the portion of my apparatus, as tubes 17, wherein cracking is effected, is illustrated generically, and that any suitable system or apparatus for cracking oil, from which reaction products may be introduced into the coking chamber B, may be used. My invention is therefore not limited to the particular mode described for cracking the high boiling distillates recovered from the fractionating column. For example, the cracked products from the tubes 17 may be passed through intermediate apparatus for further treatment of any kind, including cracking, before passing to the chamber B. Or the pressure reducing valve 18a may be omitted and the oil in tubes 17 maintained under the pressure existing in the coking chamber B, in which by regulating valve 11a may be maintained any suitable pressure.

Temperature conditions in the different parts of the system may vary. In general, however, it is preferable to heat the heavy oil before introduction into the chamber B to a temperature below that of incipient cracking, but preferably at least to 400° F. When the furnace A is utilized as part of the preheating system (it being understood that the furnace A may be omitted and preheated oil introduced into the chamber B

through the line 8), it is preferable that the temperature attained by the oil in the tubes 9 shall be below that of incipient cracking, to ensure prevention of objectionable deposition of coke or carbonaceous material within those tubes. 80

However, utilization of the preheaters, as exchanger H and/or coil 3, is of advantage even in those cases where the oil attains in the tubes 9 a temperature at which more or less cracking occurs. 85

The temperature attained by the oil in the coil 17 is preferably in excess of 800° F. to effect considerable cracking. In general, however, the cracking system or zone generically represented by the coil 17 may be operated under any suitable conditions, as to temperature and pressure, and generally such as are commonly utilized in the cracking of gas oil or the like. 90

It will be apparent from the foregoing that my invention contemplates two cooperative cracking systems, one of which includes a cracking zone, such as the chamber B, in which substantially all of the cracking of heavy oil is effected, such oil preferably having previously been preheated and maintained at or raised to 100 its cracking temperature, whereby coke, lower boiling oils and gas are formed, by introduction thereto of reaction products from the other or second cracking zone in which is cracked a lower boiling oil, derived either from a separate source 105 or from the first cracking zone, or comprising a mixture of oil from a separate source with oil derived from the first cracking zone. 110

For brevity in the appended claim the term "heavy oil" refers to oil operated upon in the first oil heating or cracking system and includes heavy oils of the character herein defined by that term; the term "intermediate boiling point" is employed generically to designate the oil lighter than said heavy oil, charged into the second 115 cracking system; and the term "low boiling point" is employed generically to designate oil constituting an ultimate product, such as cracked naphtha, gasoline or other oil of boiling point lower than that of the oil charged into the cracking and coking system. 120

What I claim is:

A combined cracking and coking process for converting hydrocarbon oil into a light distillate and coke as final products that comprises retaining hydrocarbons maintained at coking temperature in a coking chamber to convert the same to a coke residue, subjecting the evolved vapors to fractionation to form a vapor fraction and a reflux condensate, condensing said vapor fraction to form the final light distillate, passing the reflux condensate through a heated coil wherein the oil is subjected to cracking, directing the resultant cracked products at cracking temperature into the coking chamber, separately 125 heating a stream of charging stock comprising a petroleum residuum to between 400° F. and a temperature at which substantial amounts of carbon would be deposited from the residuum as the heating proceeds by subjecting said residuum 130 to indirect heat exchange with uncooled vapors leaving said coking chamber, and directing the heated stream into the coking chamber, and introducing an unheated gas-oil charging stock 135 into the heated stream of petroleum residuum 140 entering the coking chamber. 145

ALBERT G. PETERKIN, JR.
